UNITED STATES PATENT OFFICE.

UNO STONE, OF LEAD, SOUTH DAKOTA.

SAFETY DEVICE FOR PISTOLS.

No. 879,018.

Specification of Letters Patent. Patented Feb. 11, 1908.

Application filed October 12, 1907. Serial No. 397,183.

To all whom it may concern:

Be it known that I, UNO STONE, a citizen of the United States, residing at Lead city, in the county of Lawrence and State of South Dakota, have invented certain new and useful Improvements in Safety Devices for Pistols; and I do hereby declare the following to be a full, clear, and exact description of the invention, such as will enable others skilled in the art to which it appertains to make and use the same.

My invention relates to a safety device for pistols or other fire arms, and the object of my invention is to provide such a device which can be easily locked and unlocked at will, so that when the said safety device is locked the pistol or other fire arm cannot be fired at all.

To these ends my invention consists in the novel combination of parts hereinafter more fully disclosed, and particularly pointed out in the claims.

Referring to the accompanying drawings forming a part of this specification, and in which like letters refer to like parts in all the views;—Figure 1 represents a side elevation of a pistol with my invention applied thereto; Fig. 2, a sectional view taken through the grip of the pistol and showing the barrel portion broken away; Fig. 3, a rear elevational view of a pistol provided with my device, with the safety lever removed, and my improvement in its closed position; Fig. 4, a like elevational view of the pistol grip with the lever removed, and my safety device in an open position; Fig. 5, a cross sectional view of the safety lever, and of my safety locking device taken on the line 5—5 of Fig. 3, showing my safety device in its closed position; Fig. 6, a like view, taken on the lines 6—6 Fig. 4, with my safety device in its open position; and Fig. 7, a perspective detached view of my improved safety lock.

In the above drawings A represents the trigger of any suitable fire arm, in this case shown as a self-acting revolver, B represents the sear, C the hammer, D a locking lever pivoted at D', and normally pressed down by the spring E and thereby preventing the hammer from being cocked.

F represents a safety lever adapted to control the locking lever D by means of a projection G contacting with the notch H in said locking lever D. This safety lever F is

pivoted at F' to the frame of the revolver, 55 and is provided with a slot I, a small distance above said pivot. Over this slot fits the thumb button J secured by a screw K to the projection M of my locking device L, which is secured to the frame of the revolver by a 60 screw N; as shown. This safety lever locking device L is provided with three openings O, P and Q, as best shown in Fig. 7, and also with two spring tongues R provided with flanges S. Through the middle opening P, 65 the screw N passes when the tongues R are closed, and the opening Q receives said screw N when the said tongues R are in their open position. The flanges S are separated when the tongues R are opened, and pass under 70 the sides T of the safety lever F, as best shown in Fig. 6, and thereby lock the same against movement. The said tongues R are separated by pressing on the thumb button J and sliding the same over the slot I downward toward the end of the pistol grip. When the said safety device L is thus moved longitudinally, the projections V, which 75 separate the openings Q and P, take against said screw N and cause the separation of the 80 said tongues R, as best shown in Fig. 4.

The operation of my device is as follows:—When the pistol is to be fired, the thumb button J is pushed to its uppermost position, shown in Fig. 2, the handle of the pistol gripped, the trigger pulled, when the pressure of the hand on the safety lever F will cause the hammer to be unlocked, then the pistol may be fired in the usual and well-known manner. When it is desired, however, to 90 prevent the locking lever D from being moved out of its locking position, from behind the hammer, the thumb button J is forced down in its lowermost position, which will spread the spring tongues R, as shown in 95 Fig. 4, and cause the flanges S to take under the sides T of the safety lever F, as shown in Fig. 6, thereby firmly locking said lever F and preventing the same from moving the locking lever D from its locking position behind the hammer C. When in this position, it is impossible for the hammer to move forward and explode the cartridge, no matter how hard the trigger may be pulled, nor how hard the safety lever F may be pressed. By 100 this means I not only provide a revolver or other fire arm, which is normally safe except when gripped for firing, but I also provide a

means for locking the normal safety means, and thereby prevent any firing at all when the said normal safety means are locked.

Having now described my invention, what I claim, is:—

1. In a fire arm, the combination of a trigger, a hammer, a locking lever normally locking said hammer, a safety lever normally adapted to move said locking lever from its locking position behind the hammer, means to lock said safety lever, and sliding means to remove said last-mentioned locking means out of their locking position, substantially as described.
2. In a fire arm, the combination of a trigger, a sear, a hammer, a locking lever D adapted to normally lock said hammer, a spring E adapted to normally force said locking lever D into its locking position behind said hammer, a safety lever F, provided with an extension G, adapted to normally contact with said locking lever D, and provided with a slot I, a button J sliding over said slot, and means connected with said button adapted to lock said safety lever F, substantially as described.
3. In a self-acting revolver, the combination of a trigger A, a sear B, a hammer C, a locking lever D, a safety lever F, provided with an extension G adapted to contact with said locking lever D, and provided with a slot I near its lower end, a locking device L provided with an extension M extending through said slot I, and a thumb button J for operating said extension M, substantially as described.
4. In a self-acting revolver, the combination of the trigger A, a sear B, a hammer C, a locking lever D, a safety lever F, provided with a slot I, a locking device L provided with the spring jaws R, means on said jaws adapted to lock said safety lever F when the said jaws are spread apart, and a thumb button J extending over said slot I adapted to operate said locking device L, substantially as described.
5. In a self-acting revolver, the combination of the trigger A, the sear B, the hammer C, the locking lever D pivoted at D', the spring E adapted to hold said locking lever in its locking position, and said locking lever provided with the notch H, the safety lever F, provided with the extension G, adapted to enter said notch H, and also provided with the slot I, the locking device L provided with the openings P and Q, the spring jaws R, the flanges S, the extension M passing through said slot I, the thumb button J secured to said extension M, and the screw N, substantially as described.
6. In fire arms, the combination with the safety lever thereof, of a locking device for said safety levers, comprising the spring jaws R, the flanges S, the holes P and Q, and the extension M, substantially as described.
7. In fire arms, the combination of the safety lever F and a locking device L provided with two spring controlled devices adapted to spread apart and underlie the edges of said safety lever and means for separating said devices at will, substantially as described.
8. In fire arms, the combination of a safety lever, and a locking device for said lever, comprising spring jaws R and flanges S adapted to lock said lever, substantially as described.
9. In fire arms, the combination of a safety lever F and a locking device provided with the holes P and Q, the spring jaws R, the flanges S, and the extension M, substantially as described.

In testimony whereof, I affix my signature, in presence of two witnesses.

UNO STONE.
